United States Patent Office

Des. 190,813
Patented July 4, 1961

190,813

BIRD FEEDER

Raymond E. McGreevy, River Forest, and Frank M. Vondrasek, Downers Grove, Ill.; said Vondrasek assignor to said McGreevy

Filed June 21, 1960, Ser. No. 61,062

Term of patent 14 years

(Cl. D31—2)

FIGURE 1 is a front perspective view taken from the right side of a bird feeder embodying our new design, the rear being substantially like the front shown;

FIGURE 2 is a top plan view thereof;

FIGURE 3 is a left side elevational view thereof; and,

FIGURE 4 is a bottom plan view thereof.

We claim:

The ornamental design for a bird feeder, as shown and described.
